MIXED OIL GAS AND WATER GAS
PRODUCTIONJoseph A. Perry, Swarthmore, Pa., assignor to The
United Gas Improvement Company, Philadel-
phia, Pa., a corporation of Pennsylvania

Application March 2, 1929, Serial No. 344,072

5 Claims. (Cl. 48—208)

The present invention relates to the production of a mixed water gas and oil gas for domestic or industrial distribution by cracking hydrocarbon fluid in an ignited fuel bed heated by periodic air heating, to reformed gas of lower specific gravity and calorific power, depositing the excess carbon released by the cracking within the fuel bed, and utilizing the excess carbon unconsumed by the air blast, in the production of water gas, by steaming 5 the fuel bed, thereby maintaining the fuel bed 10 free and open.

The object of the present invention is to provide an improved method of operation in the production of such mixed gas whereby the capacity 15 of the apparatus employed is materially increased.

Although it is possible to utilize other apparatus, the process may be conveniently and efficiently performed in the ordinary carbureted water gas set.

20 The invention will be described in connection with the accompanying drawings which form a part of this specification, and in which

Figure 1 is a side elevation and partial vertical cross-section of a so-called down-run or back-run carbureted water gas set in which my invention 25 may be performed, and

Fig. 2 is a side elevation and partial vertical cross-section of a carbureted water gas set provided with a reverse steam connection and with 30 additional gas take-off, in which my invention may also be performed.

Referring to Fig. 1, 1 is the water gas generator provided with the fuel bed 2, and further provided with the air blast supply means 3, and the 35 steam supply means 4 for up-steaming. Steam supply means 5 having valve 55 therein may be provided for down-steaming. The generator is further provided with hydrocarbon fluid supply means which may be the hydrocarbon gas supply 40 means 6 having valve 66 therein for passing the gas downward through the fuel bed and the supply means 7 having valve 77 therein for passage upward through the fuel bed. If oil is to be cracked in the fuel bed, the oil supply means 8 having valve 88 therein may be provided. The generator is further provided with the gas off-take 45 9 provided with the valve 10, and leading from below the fuel bed to place of storage. The generator is in communication through connection 11 with the carbureter 12. The carbureter is provided with hydrocarbon fluid supply means which may be the hydrocarbon liquid supply means 13 having valve 113 therein, or the hydrocarbon gas 50 supply means 14 having valve 114 therein. The

carbureter may be further provided with the steam supply means 15 having valve 115 therein.

The carbureter is in communication through connection 16 with the superheater 17. The superheater may be provided with the steam supply 60 means 18 having valve 118 therein, for down-steaming the fuel bed. The superheater is provided with the off-take 19 provided with the valve 20 leading to the wash-box 21. 22 is the off-take from the wash-box to place of storage. The off-take 9 from the generator may lead to place of storage through wash-box 21 by a connection not shown, or through another wash-box. 23 is the superheater stack valve.

In operation, assuming the fuel bed of coal or 70 coke in the generator to be ignited, the fuel bed is blasted with air supplied at 3, the resultant air blast gases passing through the carbureter and superheater, where their combustion is completed with air supplied at 24, and their heat stored in 75 these vessels.

After sufficient heat has been stored in the fuel bed, carbureter and superheater, the air blasting is terminated. Now a downward passage of hydrocarbon gas may be made by admitting, for 80 instance, refinery oil gas or other high calorific value hydrocarbon gas such as natural gas through 6. This gas is cracked in the fuel bed, with the deposition therein of its excess carbon, to reformed gas of lower calorific power and specific gravity which is led off through off-take 9 to place of storage.

At the same time fluid hydrocarbons, for instance, gas oil, naphtha, gasoline, propane, or butane may be admitted to the carbureter through supply means 13, and vaporized therein. Some steam through supply means 15 may be simultaneously admitted to the carbureter to carry the oil vapors and protect them from over-cracking with undesirable deposition of carbon 95 in the checkerbrick. The valve 20 in the superheater off-take is set to equalize the resistance of the fuel bed and allow the passage of the oil vapors and steam through the carbureter and superheater where the oil vapors are fixed or lightly cracked, without drawing through the carbureter and superheater the oil gas supplied to the generator top. The steam and lightly cracked oil gas pass to the wash box and thence to place of storage. The lightly cracked oil gas from the superheater is mixed with the more completely cracked reformed gas from the generator either in the wash-box or in place of storage.

The above step may be followed by an upward passage of hydrocarbon gas through the fuel bed, 110

- the gas being supplied through means 7. The resultant reformed gas passes through the carbureter and superheater where it may or may not be carbureted with oil supplied at 13, and from thence through the wash-box to place of storage.
- At intervals, steam is passed through the fuel bed to produce water gas, reacting with the deposited excess carbon unconsumed by the air blast, maintaining the fuel bed free and open.
- 10 Uprun water gas may be carbureted in its passage through the carbureter and superheater. Down run water gas passes from the generator through off-take 9 to place of storage. It desired, the step of water gas production may follow the air blasting operation, instead of the hydrocarbon fluid cracking, or cycles of air blasting and water gas production may be interposed between cycles of air blasting and hydrocarbon fluid cracking.
- 15 20 Instead of supplying oil to the carbureter a hydrocarbon gas may be supplied in which case the carbureter and superheater are relieved of the work of vaporization and are utilized solely to lightly crack the gas. If desired, oil may be supplied to the generator as through means 8, in which case the fuel bed performs the work of vaporization as well as cracking the resultant oil vapors.
- 25 Referring to Fig. 2, the same numbers refer to identical parts of the apparatus as in Fig. 1. In Fig. 2, however, there are the following additional provisions:
- The connection 11 between the generator above the fuel bed and the carbureter is provided with valve 25, and an additional connection 26 is provided between the generator and the carbureter provided with the valve 27. The generator is further provided with the additional gas off-take 28, provided with valve 29.
- 30 35 40 45 50 55 60 65 70 75 The method of operation described in connection with Fig. 1 may be performed by utilizing the apparatus of Fig. 2. Some modifications of the above method are also possible in the case of the apparatus of Fig. 2.
- The reformed gas produced by passing hydrocarbon gas upwardly through the fuel bed may be led directly to storage as well as the reformed gas produced in a downward passage. During such upward passage with valves 10, 25 and 27 closed, and valve 29 opened, the reformed gas is led off through gas off-take 28 without passing through the carbureter and superheater. The carbureter and superheater may be simultaneously devoted only to the light cracking of other hydrocarbon fluid during the upward reforming run in the generator, as well as the downward reforming run. This hydrocarbon fluid may be the same kind of hydrocarbon fluid as that introduced to the generator.
- If desired, instead of employing steam to carry the oil vapors and oil gas through the carbureter and superheater to the wash-box, a small amount of gas which has been reformed in the generator may be permitted to pass from the generator through the valves 25 and 27, depending on whether the reforming passage is up or down. This small quantity of reformed gas serves to carry the oil vapors or oil gas through the carbureter and superheater and protect it from over-cracking. The remainder of the reformed gas is led off directly to the wash-box from off-takes 28 and 9.
- Steaming of the fuel bed with the production of water gas may be performed as described in connection with Fig. 1.
- The improvement in general terms includes operating the generator and the heat storage vessels in series during the air blasting operation and in parallel during the hydrocarbon cracking operation or in series and parallel during the latter operation.
- During the passage of hydrocarbon fluid through the fuel bed, the carbureter and superheater are devoted solely to the cracking of other hydrocarbon fluid and the capacity of the apparatus as a whole is very materially increased.
- It will be obvious to those skilled in the art to which the invention relates that modifications may be made in details of procedure and in matters of mere form without departing from the spirit of the invention which is not limited to such matters or otherwise than the prior art and the appended claims require.
- I claim:
1. The process of making mixed water gas and oil gas, which process, when practiced in an intercommunicating generator and heat interchanger includes the following steps: one step being, providing an ignited fuel bed in the generator, air blasting the fuel bed in the generator and the heat interchanger in series, and burning the blast gas in the heat interchanger thereby heating said interchanger; another step being, simultaneously passing fluid hydrocarbon in two separate streams, one stream passing through the generator and fuel bed depositing carbon therein and the other steam passing through the heated heat interchanger, cracking said fluid hydrocarbon in said generator and in said heat interchanger, leading off the resulting gases separately from the generator and from the heat interchanger, and simultaneously introducing some of the gas from the generator to the said heat interchanger and passing it through the heat interchanger and out of the same.
2. The process of making mixed water gas and oil gas, which process, when practiced in an intercommunicating generator and heat interchanger, includes the following steps: one step being, providing an ignited fuel bed in the generator, air blasting the fuel bed in the generator and the heat interchanger in series, and burning the blast gas in the heat interchanger thereby heating said interchanger; the second step being, simultaneously introducing a supply of oil to the generator and a supply of oil gas to the heat interchanger, simultaneously passing the resulting oil gas downwardly in two separate streams, one stream through the generator and fuel bed depositing carbon therein, the other stream through the heated heat interchanger cracking said oil gas in said generator and in said interchanger, and leading off the resulting oil gases separately from the generator and from the heat interchange vessel; and a third step being, steaming the fuel bed and consuming excess carbon deposited therein and unconsumed by the air blast and producing water gas, carbureting the water gas with hydrocarbon in said heat interchanger; and admixing the three newly made gases.
3. The process of making mixed water gas and oil gas, which process, when practiced in an intercommunicating generator and carbureter and superheater, includes the following steps: one step being, providing an ignited fuel bed in the generator, air blasting the fuel bed and the carbureter and the superheater in series and burning the air blast gas in the carbureter and

superheater thereby heating said carburetter and said superheater; the second step being, simultaneously introducing a supply of oil to the generator and a supply of oil gas to the carburetter, 5 simultaneously passing the resulting oil gas downwardly in two separate streams in parallel, one through the generator and the other through the heated carburetter and superheater, cracking said oil gas in said generator and in said carburetter 10 and superheater, and leading off the newly made gases separately from the generator and from the superheater to storage; and another step being, generating water gas by steaming the fuel bed; and admixing the water gas with the other 15 gases.

4. The process of making mixed water gas and oil gas, which process, when practiced in an intercommunicating generator and carburetter and superheater, includes the following steps: one 20 step being, providing an ignited fuel bed in the generator, air blasting the fuel bed and the carburetter and the superheater in series, and burning the air blast gas in the carburetter and superheater thereby heating said carburetter and said 25 superheater; another step being, simultaneously introducing a supply of oil to the generator and a supply of oil gas to the heat interchanger, simultaneously passing the resulting oil gas downwardly in two separate streams in parallel, one 30 through the generator and the fuel bed therein and the other through the heated carburetter

and superheater, cracking said oil gas in said generator and in said carburetter and superheater, and leading the newly made gases separately from the generator and from the superheater to storage; and another step being generating blue water gas by steaming the fuel bed, carburetting the water gas with hydrocarbon in the carburetter and superheater; and admixing the carburetted water gas with the other two gases.

5. The process of making mixed oil gas and water gas, which process, when practiced in an intercommunicating generator and carburetter and superheater, includes the following steps: one step being, providing an ignited fuel bed in the generator, air blasting the fuel bed and the carburetter and the superheater in series, and burning the blast gas in the carburetter and superheater thereby storing heat in said carburetter and superheater; another step being, simultaneously passing oil gas and steam downwardly into and through the carburetter and superheater, and hydrocarbon oil downwardly through the generator in separate streams in parallel, cracking the resulting oil gas in said generator and in said carburetter and superheater, leading off the gases from the generator and from the superheater; and another step being, generating water gas by steaming the fuel bed; and admixing the oil gases and the water gas.
